COMBINED STORAGE DRAWER AND SHELF UNIT

Walter Mueller, Zurich, Heinrich Gerhard, Haggendorf,
and Dieter Stierli, Basel, Switzerland, assignors to
Interluebke Gebr. Luebke KG, Wiedenbruck, Germany

Filed Jan. 11, 1973, Ser. No. 322,702

Claims priority, application Germany July 12, 1972

Term of patent 7 years

Int. Cl. D6—04

U.S. Cl. D6—166

FIG. 1

FIG. 6

FIG. 2

FIG. 3

FIG. 4

FIG. 5

FIG. 1 is a perspective view of a combined storage drawer and shelf unit incorporating our new design;

FIG. 2 is a front view of a combined storage drawer and shelf unit, seen in direction of arrow 2 in FIG. 1;

FIG. 3 is a side view of a combined storage drawer and shelf unit, seen in direction of arrow 3 in FIG. 1;

FIG. 4 is an opposite side view of a combined storage drawer and shelf unit;

FIG. 5 is a rear view of a combined storage drawer and shelf unit; and

FIG. 6 is a top view of a combined storage drawer and shelf unit.

We claim:

The ornamental design for a combined storage drawer and shelf unit, substantially as shown.
